UNITED STATES PATENT OFFICE.

JAMES SHUBAEL FOWLER, OF ST. ELMO, TENNESSEE.

SIRUP-PUMP.

SPECIFICATION forming part of Letters Patent No. 414,513, dated November 5, 1889.

Application filed June 19, 1889. Serial No. 314,781. (No model.)

To all whom it may concern:

Be it known that I, JAMES SHUBAEL FOWLER, a citizen of the United States, residing at St. Elmo, in the county of Hamilton and 5 State of Tennessee, have invented certain new and useful Improvements in Sirup-Pumps; and I do hereby declare that the following is a full, clear, and exact description of the same, reference being had to the annexed drawings, 10 making a part of this specification, and to the letters and figures of reference marked thereon.

This invention relates to certain new and useful improvements in pumps designed more 15 particularly as a sirup-pump; and it has for its object to provide a device of this character which shall be efficient in use and simple in construction, providing for the alternate opening and closing of the inlets and outlets, 20 and preventing waste from dripping after the required amount of liquid has been pumped.

The invention consists in the peculiar combinations and the construction, arrangement, and adaptation of parts, all as more fully 25 hereinafter described, shown in the drawings, and then particularly pointed out in the appended claims.

The invention is clearly illustrated in the accompanying drawings, which, with the letters of reference marked thereon, form a part 30 of this specification, and in which—

Figure 1 is a perspective view of my improved pump. Fig. 2 is a longitudinal section through the same. Fig. 3 is a cross-section on the line xx of Fig. 2. Fig. 4 is a cross-section on the line yy of Fig. 2. Fig. 5 is a 35 perspective view of the piston-head detached.

Like letters of reference indicate like parts throughout the several views in which they 40 occur.

Referring now to the details of the drawings by letter, A designates a cylinder of suitable size and material, open at one end and at the other provided with external screw- 45 threads a to receive the internal threads of a detachable cap B. This cylinder is formed near its capped end with a tapered externally-threaded portion b , adapted to be screwed into the cask, barrel, or other receptacle the 50 liquid from which it is designed to remove. Between this threaded portion and the capped

end of the cylinder is a discharge-spout c . This cylinder is provided upon diametrically-opposite sides with longitudinal slots d , which are the inlet-ports into the pump.

55

C is an inner cylinder or tube of such a size as to work snugly within the cylinder A, and is also provided upon diametrically-opposite sides with longitudinal slots e , of the same size in width as those in the cylinder A, and 60 adapted to register therewith at intervals, as will hereinafter appear. At its open end this inner tube or cylinder is formed with a notch f , the end walls of which are adapted to engage with a stop-pin g on the inner wall of 65 the outer cylinder, as shown in Fig. 2, to limit the revolution of the inner tube. The other end of the inner tube has a head h at a short distance from the end, leaving a chamber i beyond said head, and j is a boss extending 70 through said chamber and through a hole in the cap B. The outer end of this boss is screw-threaded and receives a nut k , as shown. D is a piston or pump rod passed through this boss and nut, and at its inner end carries a piston 75 or plunger head E, formed of the disk l , preferably of metal, and the leather or equivalent disk n . A transverse piece m is secured across the face of the leather disk, and projects beyond the same, so as to extend through 80 the slots in the inner tube, the leather of the disk also being extended to correspond with the said cross-piece. The piston or pump rod is screw-threaded through this piece and through the metal and leather disks, and upon 85 the other side is provided with a nut o , all so arranged that by turning the handle p to the piston-rod the inner tube will be given a half-revolution, for a purpose hereinafter described.

90

The operation is as follows: With the parts constructed and arranged as above set forth and shown the device is screwed into the barrel by means of the threaded portion b , and the inner tube turned so as to make its 95 slots register with those in the outer cylinder. The handle is then turned so as to make one of the slots in the inner tube register with the discharge. Then by pulling out the piston, the piston will bring out the liquid to the discharge-spout. By turning the handle of the 100 piston-rod the inner tube can be given a half-

revolution when desired to close the inlet openings of the outer tube by bringing the solid portions of the inner tube coincident with the slots in the outer tube, as shown in Fig. 2. The inner tube can be turned back and forth at will at any point of the stroke of the piston, thus opening and closing the inlets and outlets alternately. By this construction the pump is arranged within the barrel, where it acts on the syrup without waiting for it to run lengthwise through a tube as heretofore, thus saving time and patience and producing a device which is speedy, certain, and positive in its action, working as readily in winter as in summer, with thick as with thin liquids.

I contemplate employing in connection with the mechanism above described a measuring or registering device whereby the amount of liquid pumped may be readily ascertained, but have not shown such contrivance in the drawings. Preferably, however, I shall employ a disk revolving on the nut on the boss or on the boss itself, said disk being properly numbered in a manner common in such devices.

In order to prevent the waste usually attending devices of this kind, occasioned by the dripping of the liquid after the desired amount has been obtained, I pivot, as at *q*, between lugs or ears *r* on the piston-rod a lever *t*, having a handle *u*, and its other end adapted to engage a stop *v* on the cap of the outer cylinder. When the piston-rod is grasped to actuate the same, the hand grasps the handle of the lever; but when the handle of the piston-rod is let free the free end of the lever engages the stop and holds the parts in their proper position. This holds the tubes with their slots not coincident, so that no liquid can enter the inner tube, and consequently none can discharge therefrom.

What I claim as new is—

1. In a pump of the character described, the combination, with the outer cylinder pro-

vided with diametrically-opposite longitudinal slots, of the inner tube provided with diametrically-opposite longitudinal slots, the solid piston-head having portions extending through the slots of the inner tube, and its rod arranged within the inner tube and adapted to have a half-revolution therewith, substantially as shown and described.

2. The combination, with the outer cylinder having longitudinal slots and the inner tube having longitudinal slots, of the piston within the inner tube and having portions extending through the slots of the inner tube, and the piston-rod passed through the piston and provided upon its inner end with a nut, said piston-rod being free to make a half-revolution and to turn the inner tube, substantially as described.

3. The combination, with the inner and outer slotted tubes, of the solid piston-head within the inner tube, and consisting of a metal disk, a leather disk and a transverse piece extending beyond the metal disk into the slots of the inner tube, and a piston-rod connected with the piston-head, substantially as shown and described.

4. The combination, with the outer cylinder formed with a tapered externally-threaded portion *b*, of the inner slotted tube, the piston within the inner tube and having portions extending through the slots of the inner tube, the piston-rod connected with the piston and adapted to give the inner tube and piston a half-revolution, and the locking-lever pivoted to the piston-rod and adapted to engage a stop on the outer cylinder, substantially as shown and described.

In testimony that I claim the above I have hereunto subscribed my name in presence of two witnesses.

JAMES SHUBAEL FOWLER.
